UNITED STATES PATENT OFFICE.

THOMAS E. JORDAN, OF MALDEN, MASSACHUSETTS.

DESIGN FOR A BARREL-TRUCK.

5,284.

Specification for Design.

Patented Sept. 14, 1920.

Application filed June 12, 1920. Serial No. 388,648. Term of patent 14 years.

To all whom it may concern:

Be it known that I, THOMAS E. JORDAN, citizen of the United States, residing at Malden, county of Middlesex, State of Massachusetts, have invented a new, original, and ornamental Design for Barrel-Trucks, of which the following is a specification, reference being had to the accompanying drawing, forming part thereof.

In the drawings, Figure 1 is a perspective view of a barrel truck showing my new design;

Fig. 2 is a front view thereof.

I claim:

The ornamental design for a barrel truck, as shown.

THOMAS E. JORDAN.
